UNITED STATES PATENT OFFICE

129,506

DESIGN FOR A PRESS

Walter Ernst and Johan A. Muller, Mount Gilead,
Ohio, assignors to The Hydraulic Development
Corporation, Inc., Wilmington, Del., a corpora-
tion of Delaware

Application March 6, 1941, Serial No. 99,389

Term of patent 14 years

To all whom it may concern:

Be it known that we, Walter Ernst and Johan A. Muller, citizens of the United States, and residents of Mount Gilead, in the county of Morrow and State of Ohio, have invented a new, original, and ornamental Design for a Press, of which the following is a specification, reference being had to the accompanying drawing, wherein:

Figure 1 is a perspective view of a press illustrating our new design.

Figure 2 is a front elevational view thereof.

Figure 3 is a side elevational view thereof.

We claim:

The ornamental design for a press, substantially as shown.

WALTER ERNST.
JOHAN A. MULLER.
